US0D1063794S

(12) **United States Design Patent** (10) **Patent No.:** **US D1,063,794 S**
(45) **Date of Patent:** **** Feb. 25, 2025**

(54) **VEHICLE TAILGATE ENCLOSURE**

(71) Applicant: **Lund Motion Products, Inc.**, Ann Arbor, MI (US)

(72) Inventor: **Anthony Nicholas Smith**, Huntington Beach, CA (US)

(73) Assignee: **Lund Motion Products, Inc.**, Ann Arbor, MI (US)

(**) Term: **15 Years**

(21) Appl. No.: **29/878,339**

(22) Filed: **Jun. 20, 2023**

Related U.S. Application Data

(63) Continuation of application No. 17/821,766, filed on Aug. 23, 2022, now Pat. No. 11,724,753, which is a continuation of application No. 17/091,554, filed on Nov. 6, 2020, now Pat. No. 11,433,953, which is a continuation-in-part of application No. 16/696,276, filed on Nov. 26, 2019, now Pat. No. 11,142,263, which is a continuation of application No. 16/202,832, filed on Nov. 28, 2018, now Pat. No. 10,518,821, which is a continuation of application No. 15/448,952, filed on Mar. 3, 2017, now Pat. No. 10,173,735, which is a continuation of application No. 13/351,191, filed on Jan. 16, 2012, now abandoned, which is a continuation of application No. 12/947,735, filed on Nov. 16, 2010, now abandoned, which is a continuation of application No. 11/924,537, filed on Oct. 25, 2007, now Pat. No. 7,841,638.

(57) **CLAIM**

The ornamental design for a vehicle tailgate enclosure, as shown and described.

DESCRIPTION

FIG. 1 is a perspective view of the vehicle tailgate enclosure embodying my new design;

FIG. 2 is another perspective view thereof;

FIG. 3 is a back view thereof;

FIG. 4 is a front view thereof;

FIG. 5 is a side view thereof;

FIG. 6 is another side view thereof;

FIG. 7 is a top view thereof; and,

FIG. 8 is a bottom view thereof.

Broken lines, where shown, are used to illustrate portions of the vehicle tailgate enclosure that form no part of the claimed design.

1 Claim, 7 Drawing Sheets
